UNITED STATES PATENT OFFICE.

AXEL H. ENGLUND, OF PHILADELPHIA, PENNSYLVANIA, ASSIGNOR TO PROTECTED RAIL BOND COMPANY, OF PHILADELPHIA, PENNSYLVANIA, A CORPORATION OF PENNSYLVANIA.

RAIL-BOND.

No. 888,980.

Specification of Letters Patent. Patented May 26, 1908.

Application filed June 16, 1904. Serial No. 212,785.

To all whom it may concern:

Be it known that I, AXEL H. ENGLUND, a citizen of the United States, residing in the city of Philadelphia, in the county of Philadelphia and State of Pennsylvania, have invented certain new and useful Improvements in Rail-Bonds, of which the following is a specification.

This invention relates to an improvement 10 in rail bonds, and has for its object to provide an improvement in the means of securing the bond to the rails of a railroad or other structure to be bonded.

I have illustrated my invention as applied 15 to bonds of the class in which the body is provided with a loop which is adapted to permit the contraction and expansion of the rails or parts of other structures to which the bonds are attached without injury to the 20 bond, and also of that type in which the body of the bond is composed of a series of thin strips arranged side by side, that is, one upon the other, in a well known manner.

It is to be understood, however, that my invention 25 may be applied to any form of bond, and is not limited to a bond having a body of any particular or special construction.

My invention resides in the novel features of construction hereinafter described, set 30 forth specifically in the claims, and illustrated in the accompanying drawings forming a part of this specification, and in which

Figure I is a side elevation of a rail bond embodying my invention shown as applied 35 underneath the bases at the joint of two abutting rails. Fig. II is a top plan view of the same. Fig. III is a side elevation of a different form of bond shown as applied to the sides of the balls of two abutting rails at 40 their joint. Fig. IV is a top or edge view of the same. Fig. V is a section of the same on the line V—V of Figs. III and IV.

In the drawings, 1 designates the abutting ends of two rails of a railroad, and 2 designates a fish-plate by means of which the said 45 abutting ends of the rails are secured together in a usual and well known manner.

Although the bond is shown as applied to the rails of a railway track, it obviously may 50 be used for electrically bonding the parts of other structures.

Referring to Figs. I and II the body of the rail bond is shown as being composed of a 55 number of groups or series 3 of flat ribbon-like strips, the strips or ribbons of each group

being arranged one upon top of the other, several groups or series of ribbons or strips being arranged edge to edge as is clearly indicated in Fig. II.

The ribbons or strips composing each group or series 3 may consist of separate disconnected lengths, or, if desired, the said strips may be formed by winding a single strip of considerable length in a well known manner, the said strips comprising or consisting of the convolutions of the said wound strip. It is to be understood, however, that it is immaterial whether the said strips are formed of a number of separate pieces or whether the said strips consist of a single 65 integral strip of considerable length wound to form a series of convolutions.

The body of the bond illustrated in Figs. III to V inclusive consists of a single group 4 of strips arranged one on top of the other, as 75 is clearly indicated. The strips constituting the bond shown in these figures as in the construction shown in Figs. I and II, may consist of separate pieces of suitable material arranged in the manner indicated or the 80 group of strips may be formed by winding a single strip of considerable length so as to form a series of convolutions, the convolutions constituting the strips, but, as stated with respect to Figs. I and II, it is immaterial 85 whether the strips consist of separate pieces or are formed by winding a single strip as described.

If desired, my invention may be applied to a bond in which the body consists of a 90 single solid piece of suitable electrical conducting material.

In each of the figures of the drawings, 5 designates the terminals of the bonds which may be formed upon or secured to the body 95 of the bonds by brazing, welding, drop-forging, or in any other manner whatsoever.

I have provided a recess or depression 7 in each of the terminals for the reception of solder or any suitable metal 8, the fusing 100 point of which is lower than the fusing point of the metal of the terminals and body portion of the bond.

The recesses or depressions 7 may be formed in any suitable manner in the terminals 5, for instance, they may be formed by cutting out some of the metal of the terminals, or by pressure exerted by a die or other suitable tool upon the said terminals.

After the depressions or recesses are 110

- formed in the terminals, they are filled with some suitable metal of the character described, so that the metal in each depression preferably, but not necessarily, projects a short distance above the surface of the body of the terminal, as indicated at 9 in Figs. IV and V. As a matter of fact, the fusible metal may be flush with or even below the surface of the body by reason of the fact that 10 upon the application of heat and pressure to the side of the terminal opposite the solder or fusible metal in the operation of attaching the bond to the rail, the fused solder or metal is forced into contact with the rail so as to 15 make a proper joint.

It will be observed that each of the recesses or pockets for the fusible metal or solder in the bonds is entirely surrounded by a wall or rim so that when the bonds are applied to a structure to be bonded, the recesses or pockets are completely closed, so that it is necessary in the use and practice of my invention that the said recesses or pockets to be filled with the fusible soldering material prior to the application of the bond to the said structure.

Prior to the application of a bond to the structure to be bonded, the surfaces of such structure, as, for instance, the rails of a railway track at the points at which the bonds are to be secured to the structure, are burnished or polished. The bonds are then applied so that the surfaces of the metal held in the recesses or pockets in the bonds are in contact with the polished surfaces upon the structure to be bonded, after which heat and pressure are applied to the bonds at the points where they are to be connected to the structure to be bonded by means of which 40 the bonds are securely attached to the material of the structure being bonded.

By reason of the application of pressure and heat, the material of the bonds is brought in very close relation to the material of the bonded structure, making both a mechanical and electrical union between the bond and structure bonded, so that an electric current may pass readily through the structure.

It happens that in the two forms of construction shown in Figs. I and II and in Figs. III to V, the recesses 7 extend across the strips or ribbons which constitute the bond and which are arranged side by side. During the process of attaching the bond to the structure being bonded, as set forth above, the fusible metal located within the recesses 7 is forced in all directions and into all interstices, however small. In consequence of this, the portions of the ribbons or strips at the points where they are connected to the material of the structure being bonded are brought into substantial and practical contact with the metal of the bonded structure, for instance, the rails of a railway track. In this manner, both the mechanical and elec-

trical union between the bond and the bonded structure are very satisfactorily made.

I do not desire to be limited to the details of construction illustrated and described herein for it is obvious that various changes 70 may be made without departure from the spirit and scope of my invention.

Having thus described my invention, I claim:—

1. A bond for electrically bonding structures comprising a series of ribbons or strips arranged one upon the other, the edges of which ribbons form flat surfaces, terminals at the opposite ends of the said bond, the said terminals being provided with recesses 80 formed in the edges of and extending across the said strips, and metal fusible at a lower temperature than that at which the material of the bond is composed is fusible located in the said recesses, the said metal in the said recesses being adapted to be partially displaced by the application of heat and pressure in the process of attaching the bond to the parts to be bonded, whereby the edges of the said ribbons or strips are brought into 90 substantial contact with the metal of the said parts to be bonded.

2. A bond for electrically bonding structures, said bond having a body portion which consists of a plurality of strips arranged one 95 on top of the other, and terminals secured at the opposite ends of the said body portions, the said terminals being provided with recesses which extend across the said strips, and a metal fusible at a relatively low temperature located in the said recesses which recesses are provided for the purpose of preventing the escape of the said fusible metal from between the said terminals and the parts of a structure to be bonded when heat 100 and pressure are applied to the terminals to 105 secure them to the said parts.

3. A rail bond having a flat terminal provided in its inner face with a solder cavity extending throughout substantially the entire length and height thereof and being of uniform depth laterally or in a direction perpendicular to the plane of the terminal, in combination with a rail, and a filling of solder in said cavity between the rail and the back 110 of the terminal.

4. A bond adapted for use for electrically bonding structures, the said bond being provided with a recess having a wall which extends entirely around the same, so that when the bond is applied to the structure to be bonded the said recess is closed on all sides.

5. A bond adapted for use for electrically bonding structures, the said bond having terminals each of which is provided with recesses, and each of which recesses has a wall or rim extending entirely around the same, whereby when the said bond is applied to the parts of a structure to be bonded, the said recesses are closed on all sides.

6. A bond adapted for use in bonding structures; whereby an electric current may pass through said structures, the said bond being provided with recesses having walls 5 extending entirely around the said recesses, fusible soldering metal located in the said recesses, the said recesses being closed on all sides when the bond is applied to the structure to be bonded, whereby the said solder-
10 ing metal must be placed in the recesses prior to the placing of the bond against the structure to be bonded.

7. A bond for electrically bonding structures, the said bond having a terminal provided in its inner face with a solder cavity
15

extending throughout substantially the entire length and height thereof, and being uniform of depth laterally or in a direction perpendicular to the plane of the terminal, in combination with the bonded structure, and 20 a filling of solder in said cavity between said structure and the back of the terminal.

In testimony that I claim the foregoing as my invention I have hereunto signed my name this 13th day of June, A. D. 1904.

AXEL H. ENGLUND.

In the presence of—

CYRUS N. ANDERSON,
THOS. K. LANCASTER.
